UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

STEAM-REGULATOR FOR TAPPED TURBINES.

1,085,132.

Specification of Letters Patent.

Patented Jan. 27, 1914.

Application filed September 14, 1912. Serial No. 720,346.

To all whom it may concern:

Be it known that I, OSCAR JUNGGREN, a citizen of the United States, residing at Schenectady, county of Schenectady, State of New York, have invented certain new and useful Improvements in Steam-Regulators for Tapped Turbines, of which the following is a specification.

This invention relates to elastic fluid turbines from which steam is extracted for industrial purposes. In these machines only part of the steam goes through the whole turbine, the other part being drawn off after passing one or more of the high pressure stages and conveyed to heating systems, dye kettles, cooking appliances or other industrial apparatus requiring steam heat.

In some cases, it is necessary that this extracted steam be supplied at a constant pressure, and the object of the present invention is to accomplish this result.

A by-pass is provided for conveying any surplus of extracted steam to a lower stage of the turbine, and this by-pass is controlled by a throttle valve connected to actuating mechanism responsive to changes in the pressure in the heating main, so that in case all the extracted steam is not required, the surplus will be diverted through the by-pass and perform useful work in the lower stages of the turbine.

In the accompanying drawings, Figure 1 is an elevation of a portion of a turbine equipped with my invention, some parts being shown in section; Fig. 2 is an elevation at right angles to Fig. 1, and Fig. 3 is a section, looking at the opposite side of Fig. 1.

In the turbine casing 1 are the bucket wheels 2 and 3. If the turbine has several stages, these wheels would probably be those in the third and fourth stages. The exhaust steam from the wheel 2 enters the chamber 4 in a separate casing suitably secured to the turbine casing 1, from which it can be carried off through the pipe 5 for heating or other industrial purposes. Adjacent to the chamber 4 is a chamber 6 communicating with the nozzles 7 for the wheel 3. Between the chambers 4 and 6 is a by-pass 8 which is controlled by a valve, preferably a butterfly valve 9. The position of this valve, and consequently the proportion of steam which passes to the heating pipe 5, depend upon

the pressure in said pipe, which acts upon 55 a movable abutment controlling said valve. I prefer to use a flexible diaphragm 10 whose periphery is tightly clamped to a plate 11. A pipe 12 is tapped through said plate and communicates with the heating pipe 5, so 60 that the diaphragm is exposed on one side to the pressure prevailing in the heating pipe, and on the other side to atmospheric pressure. The pressure in the heating main which will be sufficient to flex the diaphragm 65 depends partly upon the stiffness of said diaphragm, but it can be adjusted within a considerable range by attaching to the diaphragm a lever 13 whose free end is connected to a tension spring 14 provided with 70 a screw 15 passing through an eye in a bracket 16 on the plate 11 and provided with a nut 17 for adjusting the tension of the spring. A rod 18 is pivoted to the lever 13 and also to a floating lever 19 whose other 75 end is connected by a link 20 to an arm 21 on the spindle of the valve 9. A lever 22 also is attached to said spindle and is suitably connected to the piston of a hydraulic motor 23 supplied with liquid under pressure, 80 such as oil from the forced lubrication system. The pilot valve 24, which controls the admission of oil to the motor, is connected to the floating lever 19.

The operation of the invention is as follows: Under normal conditions, the by-pass throttle valve 9 will stand partly open to permit a portion of the steam exhausting from wheel 2 to pass to wheel 3, retaining only enough to keep the pressure in the 90 heating pipe 5 at a predetermined constant value. Should the pressure in pipe 5 increase for any reason, say from the shutting down of some of the heating apparatus, the diaphragm 10 will lift the floating lever 19 95 and the pilot valve 24, admitting pressure to the front end of the motor 23 and thereby opening the valve 9 a little wider so that a large proportion of the steam will flow to the wheel 3. This will reduce the 100 normal pressure in the heating system and restore it to normal. The arm 21 turns with the valve 9 and draws down the floating lever, so that the pilot valve will be returned to its normal position and the valve 105 9 held in its new position; the arm 21 and link 20 constituting the follow-up device. Small changes in steam pressure are suffi-

cient to operate this device, which will hold the pressure in the heating system at or close to a predetermined constant value.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

15 The combination with a turbine comprising a plurality of stages, of a separate casing secured to the turbine casing and having a partition dividing it into a plurality of chambers, one of said chambers communicating with one stage of the turbine and the other communicating with a lower

stage, and there being an opening through said partition connecting said chambers, a conduit leading from the first mentioned one of said chambers through which steam 25 may be drawn for industrial purposes, a rotary valve in said opening, a motor for operating said valve secured to said casing and having its piston connected with an arm on the valve spindle, and a device for controlling the supply of fluid to said motor and the actuation of said valve which is responsive to the pressure of the steam on the side of said valve from which steam is drawn as aforesaid. 30 35

In witness whereof, I have hereunto set my hand this 13th day of September, 1912.

OSCAR JUNGGREN.
